UNITED STATES PATENT OFFICE.

THOMAS O. CRITZ, OF RICHMOND, VIRGINIA.

VALVE-GRINDING TOOL.

1,214,138.

Specification of Letters Patent. Patented Jan. 30, 1917.

Application filed July 8, 1914. Serial No. 849,774.

To all whom it may concern:

Be it known that I, THOMAS O. CRITZ, a citizen of the United States, residing at Richmond, in the county of Henrico and State of Virginia, have invented certain new and useful Improvements in Valve-Grinding Tools, of which the following is a specification.

My invention relates to improvements in tools for cutting valve seats in gas engines.

The object of my invention is to provide a tool of this character which is adapted to be readily used on the ordinary gas engine, and in which the valve stem guide of the engine forms a guide for centering the tool in respect to the seat and at the same time forming a bearing for the lower end of the tool.

Another object of my invention is to provide a tool of this character in which the cutting tool is provided with two cutting edges and in which either edge can be adjusted to do the cutting and at the same time providing means for rigidly holding the cutting tool in its adjusted position.

A still further object of my invention is to provide a simple, cheap and more effective tool of this character having certain details of structure hereinafter more fully described.

In the accompanying drawings: Figure 1 is a vertical sectional view of an engine cylinder showing the valve removed and my improved tool in its operative position; Fig. 2 is a vertical sectional view of the tool, showing the parts in their disassembled position; and Fig. 3 is a perspective view of my improved tool. Fig. 4 is a detail view of the bushing.

Referring now to the drawings, 1 represents an engine cylinder and 2 the valve seat having the web 3 below carrying the opening 4, in which the valve stem moves vertically, all of which is well understood and needs no further description. The head of the cylinder 1 is provided with an enlarged screw-threaded opening 5, closed by a plug, and whereby access may be had to the valve and the same readily removed.

My improved tool consists of a body portion 6 of an elongated cylindrical form and having at its upper end a squared portion 7, adapted to receive a wrench 8, whereby the said body portion is rotated, as will be hereinafter more fully described. The said

body portion 6 is provided with a vertical screw-threaded opening 9 communicating with the upper end thereof. Below the screw-threaded opening 9, the body portion is provided with a smooth opening 10, which intersects a transverse opening 11 adjacent the lower end of the body portion. This transverse opening 11 is of a rectangular form in cross-section and into which fits the cutting tool 12.

The cutting tool 12 is of a rectangular form in cross-section and is of a length considerably greater than the diameter of the body portion 6 of the tool. The cutting tool at each end has cutting edges 13 and 14, which are of different shapes, curves or cutting angles, so that valve seats of different shapes and curves may be more readily ground to conform to the shape of the valve.

Loosely fitting within the smooth opening 10 is a bar 15, which is adapted to engage the cutting tool 12. Screwed within the opening 9, at the upper end of the tool, is a set screw 16 which is screwed down upon the rod 15 and forces the same downwardly into engagement with the tool 12, and locks it in its adjusted position, as clearly shown in Fig. 1 of the drawings. By this structure, it will be seen that the tool can be adjusted to cause one end to engage the valve seat and be held in its adjusted position.

The lower end of the body portion 6 is rounded, as indicated at 17, and is provided with an elongated stem portion 18 which enters the valve stem opening 4, and whereby the tool is rotatably held in its proper position and centered in respect to the valve seat 2.

The tool, as heretofore described, is rotated by means of a wrench 8, which causes the tool to engage the valve seat and face the same. While I have shown the wrench 8, it will be understood that any other form of instrument can be applied to the squared upper end for rotating the same, and by releasing the set-screw the cutting tool can be adjusted by inserting a screw driver through the opening 5 without removing the tool from the cylinder.

By the use of a bushing, as shown in Fig. 4, the depending stem portion 18 of the tool is held in proper position in cylinders having valve stem openings of a greater diameter.

105

110

Having thus described my invention, what I claim as new and desire to secure by Letters Patent, is:

1. A tool of the character described, comprising a cylindrical body portion having an angular upper reduced end and a transverse angular opening adjacent its lower end, a cutting tool adjustable in said opening and extending beyond the sides of the body portion, a screw extending downwardly through the body portion from its upper end and adapted to lock the facing tool in its adjusted position, and a reduced elongated rod carried by the lower end of the body portion.
2. A tool of the character described comprising a body portion, means for rotating the same, an elongated bearing rod carried by the lower end of the body portion, a cutting tool transversely adjustable through the tool, and means extending through the upper end of the body portion for locking the cutting tool in its adjusted position, whereby the tool can be adjusted to its proper position after the tool is inserted in the cylinder.

3. A tool of the character described, comprising a cylindrical body portion having an angular upper end and a transverse angular opening adjacent its lower end, said body portion having a longitudinal opening extending from its upper end and intersecting the transverse opening and having its upper end screw-threaded, a cutting tool in said transverse opening and extending beyond the sides of the body portion, a rod within the longitudinal opening and engaging the cutting tool, a screw within the threaded end of the longitudinal opening and engaging the rod and forcing the same into engagement with the cutting tool, an elongated rod carried by the lower end of the body portion, and a removable sleeve on said rod, substantially as shown and described.

In testimony, whereof I affix my signature in presence of two witnesses.

THOMAS O. CRITZ.
